CONTAINER CLOSURE

Jay Bernard Eisen, Yonkers, N. Y., assignor to
Ferdinand Gutmann & Co., Brooklyn, N. Y., a
corporation of New York

Application August 12, 1933, Serial No. 684,786

6 Claims. (Cl. 215—43)

The invention relates to a container closure, and more particularly to a "re-seal" closure of the type in which the shell of the closure, in addition to the usual cushion disk or gasket covering its entire inner face, has mounted therein a disk of thin material, the surface of which adjacent its edge is permanently bonded or cemented to the top of a container neck during the application of the cap to the container.

10 In the type of cap to which the invention relates, a permanent effective inner seal is secured by means of said disk of thin material, which ordinarily is a cellulose product of a type known commercially as "cellophane". The material of

15 the disk, however, may vary, as may the cementing medium used for securing it to the neck of the bottle or other container, such being determined largely by the character of the material being bottled. Whatever the material used in 20 the disk, however, it must be substantially non-absorbent and gas impervious and be of a thinness which is readily rupturable in order to permit its removal when it is desired to have access to the contents of the bottle.

25 Furthermore, the inner face of the cushion disk or gasket of a re-seal closure must possess the same properties of being non-absorbent and gas impervious as the inner sealing disk, since after the removal of this inner disk, the closure, with 30 its contained cushion disk or gasket, is used for again sealing the bottle after a portion of the contents has been removed.

Closures of the type above referred to were known prior to my invention, and have been extensively used in the packaging of drugs, flavoring extracts, foodstuffs and various other substances, such use running into the millions.

Prior to my invention, the practice in producing caps of the inner seal, re-seal type involved 40 the cutting of disks for the inner seal of a diameter slightly in excess of the maximum inner diameter of the skirt of the shell of the closure, so that the inner seal disk was frictionally held within the closure shell during shipment and 45 while in the capping machine. Said disks were cut from a web of the material just prior to delivering within the shell. With closures having a skirt formed of Bakelite or other phenol formaldehyde or similar compounds, the depth of 50 the threads is such that during delivery of the inner seal disk to the shell there is always likelihood of the wrinkling of the disk, or of a bulging thereof to an extent to at times allow the edge of the skirt of one shell to mutilate, or to dislodge the inner seal of another closure, while

in the capping machine. Furthermore, since the thickness of the material of the inner seal disk may be only between .001 and .003 of an inch, it does not possess a degree of rigidity which will at all times ensure an effective frictional contact between the edge thereof and the skirt of the bottle, and any wrinkling or bulging not only lessens this frictional contact but permits air to enter between the disk of the inner seal and the cushion disk, so that mere agitation of 60 the closures may result in the dislodgement of the inner seal disk and its escape from the shell. With metal shells the same conditions are present, but to a lesser degree.

It is highly desirable that each closure, as it 65 is applied to a container, shall contain a disk for forming the inner seal, and that this inner seal disk shall be readily separable from the closure shell and its container cushion disk or gasket, as the re-seal portion of the closure is 70 being removed, to avoid accidental rupture of said disk. In other words, the essential characteristic of a closure of the type to which the invention relates is that with the removal of the so-called "re-seal" cap, the disk cemented to the 75 neck of the bottle shall remain upon the bottle in an imperforate condition so as to prevent the unwarranted removal of the contents of the container by unscrupulous persons who may be inclined to dilute such contents.

With the above conditions in mind, I have provided a closure of the type referred to above, wherein the disk for forming the inner seal will remain within the shell of the closure, notwithstanding that the closure may be subjected to 90 violent shocks or jars or violent agitation during transportation thereof and while in a capping machine. The means employed for preventing the accidental escape of the inner seal disk from the shell avoids necessity for the use of any 95 bonding medium between the disk and the cushion disk within the shell of a closure, or of frictional contact between the edge of the disk and the skirt of the closure.

By constructing a closure in accordance with 100 the invention, it is, therefore, possible to make the inner seal disk of a diameter materially less than the maximum inner diameter of the skirt of the closure, thus permitting said disk to be laid flat upon the face of the cushion disk or sealing gasket within the closure shell, and avoiding any possibility of wrinkling or buckling of the material of said inner sealing disk, either during 105 its assembly in the closure structure or when applying a closure to a bottle. Wrinkling of the 110

material of the inner sealing disk is undesirable, particularly as it may prevent the formation of a tight seal between the edge portion of said disk and the top of the neck of a container.

6 The manner of combining the inner sealing disk in the closure structure is such as to ensure the turning of the shell, its contained cushion disk or sealing gasket and the inner sealing disk during the application of a closure to the container, and permits a free turning of the cushion disk or sealing gasket in relation to the inner sealing disk during the removal of the re-seal cap from the container when it is desired to have access to the contents thereof. This free turning movement of the re-seal portion of the closure in relation to the inner sealing disk is highly desirable during the removal of the re-seal portion of the closure from the container since it avoids likelihood of the rupture of the inner sealing disk from turning movement of the re-seal cap.

10 The material used in causing the retention of the inner sealing disk within the shell of the closure may vary widely, although it must be innocuous to the container contents which come into contact therewith upon the readjustment of the closure to the container following the removal of the inner sealing disk. It must also be substantially non-volatile or non-tacky to an extent to ensure the retention of the inner sealing disk within the shell over fairly long intervals, since the closures may be stored for a considerable time before application to a container.

15 The invention consists primarily in a container closure embodying therein a shell having a skirt provided with means adapted to engage complementary means upon the neck of a container in applying a closure thereto, a cushion disk or sealing gasket within said skirted shell, a disk within said skirted shell for forming an inner seal, and an air excluding stratum of non-volatile and non-tacky fluid between said inner seal disk and said cushion disk or sealing gasket, whereby accidental escape of said inner seal disk from the shell is prevented and relative movement and separation of said cushion disk or sealing gasket and said inner seal disk are facilitated; and in such other novel features of construction and combination of parts as are 20 hereinafter set forth and described, and more particularly pointed out in the claims hereto appended.

25 Referring to the drawing,

Fig. 1 is a bottom plan view of a closure embodying the invention upon an enlarged scale; and

Fig. 2 is a section on the line 2—2 of Fig. 1.

30 Like numerals refer to like parts in both of said views.

35 In the embodiment of the invention shown in the drawing, it is illustrated in connection with a well known type of closure used with wide-mouthed glass bottles or jars. This closure has a metal shell consisting of a top 10, and a skirt 11 provided with screw threads 12, or other wedging devices adapted to engage complementary means upon the neck of a bottle to permit the attachment of the closure to the bottle by a turning movement of the closure.

40 Within the skirt 11 and ordinarily cemented to the top 10 of the shell is a cushion disk or sealing gasket 13, which may take a wide variety of forms. In some instances this disk or gasket is formed of natural or composition cork, while 45 in other instances it is made of a soft paper

5 provided with an outer protecting surfacing 14 composed of a heavy hard paper, known to the trade as krafts, express or cartridge paper having a varnished surface thereof presented toward the bottom of the skirt, and the other face thereof, under some conditions, being cemented to the cushion disk 13. It is sometimes the practice, however, to merely retain the cushion disk and its face in the shell by frictional engagement therewith with the inner wall of the skirt.

6 When a disk of natural or composition cork is used, such materials possess inherent characteristics of being substantially non-absorbent and gas impervious. A varnished paper facing 14 for a cardboard or other cushion disk presents toward the contents of the container, a material which is substantially non-absorbent and gas impervious. Whatever the material of which the cushion disk or sealing gasket may be made, it must possess the qualities of being substantially non-absorbent and gas impervious, these characteristics being essential to the cushion disk or sealing gasket of a closure embodying the invention.

10 Also within the closure shell is an inner seal disk 15 of a thin material which is non-absorbent, gas impervious and immune to deterioration from the action of the contents of the container thereon. This disk when applying a closure to a container has a portion thereof, adjacent its edge, cemented to the top of the neck of the container to form an inner seal which will remain intact notwithstanding the removal of the metal shell and its contained cushion disk or sealing gasket from the container.

15 While the material of which this disk is made may vary to adapt it for use with different substances to be packaged, a cellulose product, known in the trade as "Cellophane", is extensively used for this purpose.

20 The diameter of the disk 15 may be slightly smaller than the maximum inner diameter of the skirt 11 so as to avoid frictional engagement between the edge of the disk and the inner surface of the skirt, and to permit the insertion of the disk through the open end of the skirt without any material buckling of the disk. Care must be taken, however, to provide an inner seal disk of sufficient diameter to completely span the mouth of a bottle and lap the top thereof to an extent 25 to permit the formation of an effective bond between same and the bottle neck, notwithstanding the maximum degree of shifting of the disk 15 within the shell. The difference in diameter may amount to one-sixty-fourth of an inch without 30 any possibility of a failure to make a proper bond between the disk and the top of the neck of the container.

25 Between the inner seal disk 15 and the non-absorbent cushion disk or sealing gasket 13—14 is 35 an interposed film or stratum of a non-volatile, non-tacky fluid shown at 16. This film or stratum may be of a highly refined mineral oil, petrolatum, glycerine or, where certain oils are being packaged, may correspond with the oil in the package. The character of the oil used must be selected to avoid contamination of the contents of a bottle or other container with what remains of the film upon the cushion disk or sealing gasket after the removal of the closure.

30 The film or stratum 16 may be applied throughout the entire area of the disk 15, or to any substantial portion of this area. Ordinarily, as a strip of the material from which the disk 15 is cut is being fed to the dies in the assembling machine, 35

it is passed over a swab saturated with the oily material so as to apply a film to the under surface of the strip or that surface presented toward the female die member. Hence, the presence of the film of oil has no tendency to interfere with the die action, and there is no tendency to smut the surface of the disk 15 presented toward the neck of a bottle with oil to an extent to interfere with the formation of the closely adherent bond between the portion of the disk adjacent its edge and the neck of the bottle.

In placing the disk within the shell, the oil film is forced into engagement with the cushion disk or sealing gasket proper, and all air is excluded from between said disk and the cushion disk or sealing gasket. With the withdrawal of the male die, atmospheric pressure will hold the disk 15 in position upon the cushion disk or sealing gasket, and the oil film will prevent air entering between said inner seal disk and said cushion disk or sealing gasket.

While the disk 15 may be slid from one position to another upon the cushion disk or sealing gasket, there is no tendency whatever for it to lift or separate therefrom, and any lifting of the disk is resisted. There is no cementing whatever of the disk 15 to the cushion disk, so that after cementitious material has been applied to the top of the neck of a container and the closure, embodying the invention, is applied thereto by the capping machine, the pressure upon the disk 15 with the compression of the cushion disk or sealing gasket causes it to turn with the cushion disk or gasket so as to cause a rotary rubbing action applied to the cement by the disk 15 in a manner to assure the effective spreading of the cement when forming the inner seal.

When removing the shell and its contained cushion disk or sealing gasket to permit access to the inner seal disk adhered to the top of the neck of the bottle or other container, the cushion disk or sealing gasket turns freely in relation to the inner seal disk so that there is no tendency toward the rupture of this seal as a result of the twisting action of a cushion disk thereupon.

The disk 15 is made from thin strip material, its thickness ranging from .001 to .003 of an inch, so that notwithstanding the toughness of the material, possibility of accidental rupture is not lacking.

The oil materials used in the film are, except at the extreme edges thereof, protected from contact with the atmospheric air, so that there is little or no tendency of the oxidation thereof to an extent to cause the hardening of the material of the film in a manner to form even a light bond between the disk 15 and the cushion disk, or sealing gasket.

Actual practice has demonstrated that with the use of a film of non-volatile, non-tacky, uncrossed material in the manner herein referred to, the likelihood of the accidental loss of an inner seal disk or film from the closure is negligible.

It is not my intention to limit the invention to the detailed construction of closure shown in the accompanying drawing and herein specifically referred to, it being obvious that such may be varied without departing from the spirit and scope of the invention.

I believe it to be broadly new to provide a closure embodying therein an inner seal disk held against accidental displacement in its relation to the cushion disk or sealing gasket by a stratum or film of a non-volatile and non-tacky fluid permitting free relative movement of the cushion

disk or sealing gasket and the inner seal disk during turning movement of either, and I intend to claim such broadly.

Having described the invention, what I claim as new and desire to have protected by Letters Patent, is:—

1. A container closure embodying therein a shell having a skirt provided with means adapted to engage complementary means upon the neck of a container in applying a closure thereto, a cushion disk or sealing gasket within said skirted shell, a disk within said skirted shell for forming an inner seal, and an air excluding stratum of non-volatile and non-tacky fluid between said inner seal disk and said cushion disk or sealing gasket, whereby accidental escape of said inner seal disk from the shell is prevented and relative movement and separation of said cushion disk or sealing gasket and said inner seal disk are facilitated.

2. A container closure embodying therein a shell having a skirt provided with means adapted to engage complementary means upon the neck of a container in applying a closure thereto, a cushion disk or sealing gasket, the exposed face of which is substantially non-absorbent and gas impervious within said skirted shell, a disk of thin flexible substantially non-absorbent and gas impervious material within said skirted shell for forming an inner seal, and an air excluding stratum of non-volatile and non-tacky fluid between said inner seal disk and said cushion disk or sealing gasket, whereby accidental escape of said inner seal disk from the shell is prevented and relative movement and separation of said cushion disk or sealing gasket and said inner seal disk are facilitated.

3. A container closure embodying therein a shell having a skirt provided with means adapted to engage complementary means upon the neck of a container in applying a closure thereto, a cushion disk or sealing gasket within said skirted shell, a disk within said skirted shell for forming an inner seal, said inner seal disk being of a relatively smaller diameter than the inner diameter of the skirt of said shell, and an air excluding stratum of non-volatile and non-tacky fluid between said inner seal disk and said cushion disk or sealing gasket, whereby accidental escape of said inner seal disk from the shell is prevented and relative movement and separation of said cushion disk or sealing gasket and said inner seal disk are facilitated.

4. A container closure embodying therein a shell having a skirt provided with means adapted to engage complementary means upon the neck of a container in applying a closure thereto, a cushion disk or sealing gasket, the exposed face of which is substantially non-absorbent and gas impervious within said skirted shell, a disk of thin flexible substantially non-absorbent and gas impervious material within said skirted shell for forming an inner seal, said inner seal disk being of a relatively smaller diameter than the inner diameter of the skirt of said shell, and an air excluding stratum of non-volatile and non-tacky fluid between said inner seal disk and said cushion disk or sealing gasket, whereby accidental escape of said inner seal disk from the shell is prevented and relative movement and separation of said cushion disk or sealing gasket and said inner seal disk are facilitated.

5. A container closure embodying therein a shell having a skirt provided with means adapted to engage complementary means upon the neck

- of a container in applying a closure thereto, a cushion disk or sealing gasket within said skirted shell, a disk within said skirted shell for forming an inner seal, and a thin film of oil between said 5 inner seal disk and said cushion disk or sealing gasket, whereby accidental escape of said inner seal disk from the shell is prevented and relative movement and separation of said cushion disk or sealing gasket and said inner seal disk are 10 facilitated.
6. A container closure embodying therein a shell having a skirt provided with means adapted to engage complementary means upon the neck of a container in applying a closure thereto, a cushion disk or sealing gasket, the exposed face 15 of which is substantially non-absorbent and gas impervious within said skirted shell, a disk of thin flexible substantially non-absorbent and gas impervious material within said skirted shell for forming an inner seal, said inner seal disk being of a relatively smaller diameter than the inner diameter of the skirt of said shell, and a film of thin oil between said inner seal disk and said cushion disk or sealing gasket, whereby accidental escape of said inner seal disk from the shell is prevented and relative movement and separation of said cushion disk or sealing gasket and said inner seal disk are facilitated. 20 25 30 35 40 45 50 55 60 65 70 75
